(57) CLAIM

The ornamental design for an elongated extension member for extension poles, as shown and described.

DESCRIPTION

FIG. 1 is a front perspective view of the front portion of an elongated extension member for extension poles showing my new design.

FIG. 2 is a fragmentary side elevational view as viewed from the lower left in FIG. 1.

FIG. 3 is a front end view as viewed from the lower right in FIG. 1.

FIG. 4 is a fragmentary side elevational view similar to FIG. 2 but viewed from the opposite side.

FIG. 5 is a fragmentary, foreshortened front perspective view of a second embodiment of my new design.

FIG. 6 is a fragmentary, foreshortened side elevational view as viewed from the lower left in FIG. 5; and,

FIG. 7 is a fragmentary, foreshortened side elevational view similar to FIG. 6 but viewed from the opposite side.

The front end view as viewed from the lower right in FIG. 5 is identical to FIG. 3.

The fragmentary broken line showing of a portion of an extension pole mounting the extension member in FIG. 1 is for illustrative purposes only and forms no part of the claimed design.

The second embodiment of the claim is shown fragmented for ease of illustration.
